UNITED STATES PATENT OFFICE

124,857

DESIGN FOR A COMBINED DIRECTIONAL SIGNAL LAMP AND SUPPORT FOR BI- CYCLES

Orlando F. Ingle and Lafayette B. Lower,
Rushville, Ind.

Application October 23, 1940, Serial No. 96,029

Term of patent 14 years

To all whom it may concern:

Be it known that we, Orlando F. Ingle and Lafayette B. Lower, residing at Rushville, in the county of Rush and State of Indiana, have invented a new, original, and ornamental Design for a Combined Directional Signal Lamp and Support for Bicycles, of which the following is a specification, reference being had to the accompanying drawing, forming part thereof.

Figure 1 is a side elevation of a combined directional signal lamp and support for bicycles, showing our new design.

Figure 2 is a front elevation thereof.

Figure 3 is a top plan view.

Figure 4 is a rear elevation.

We claim:

The ornamental design for a combined directional signal lamp and support for bicycles, as shown.

ORLANDO F. INGLE,
LAFAYETTE B. LOWER.
